UNITED STATES PATENT OFFICE.

PETER BURD JAGGER, OF LONDON, ENGLAND, ASSIGNOR TO QUEBEC SAVINGS AND TRUST COMPANY, OF MONTREAL, CANADA.

MOLD FOR FORMING CONCRETE PIPES.

1,157,987.

Specification of Letters Patent.

Patented Oct. 26, 1915.

Application filed March 4, 1911. Serial No. 612,393.

To all whom it may concern:

Be it known that I, PETER BURD JAGGER, a subject of His Majesty the King of England, residing at Carlton Studios, Carlton 5 Vale, Maida Vale, London, N. W., England, have invented certain new and useful Improvements in Molds for Forming Concrete Pipes, of which the following is a specification.

- 10 This invention relates to the manufacture of pipes, particularly sewer pipes, of concrete or ferro-concrete by introducing an artificial conglomerate composed of some hard substance termed the aggregate and a 15 cementing material called the matrix into a mold longitudinally thereof, and it has for its object to provide for this purpose an improved construction of sheet metal mold comprising a contractile core, an outer expansible horse-shoe shaped casing of sheet metal having longitudinal edges which form the inlet opening arranged in a horizontal plane and which when released springs outwardly and in opening acts through its sides 20 25 30 35 40 45 50 55 60 65 70 75 80 85 90 95 100 105 110
- acting as lifting supporting members to automatically bodily separate and free itself from the pipe and take the weight of the casing off the back of the pipe, end plates to which said core and said expansible casing are removably secured, bearing surfaces on the facing sides of the said plates said bearing surfaces following the contour of the exterior of the pipe and being adapted to permit the expansible casing to so separate and free itself from the pipe when said casing is released, said end plates being each provided with a central opening within which the said core is adapted to be expanded, and means for holding said expansible casing in fixed relation to said core and in fluid tight relation to said end plates. With such a mold I am enabled to produce, for example, a pipe having a flat base and a spigot and faucet complete, with a minimum amount of labor, it being only necessary after assembly of the mold parts to feed and pack the conglomerate therein until the mold is completely filled. In this way I can insure the production of pipes that are interiorly and exteriorly uniform and identical such as cannot be obtained in cases where the inner core is of a yielding material and adapted to be inflated as has been proposed.
- By arranging a temporary addition to the mold to form a continuation of the casing

adjacent to the admission opening when the casing is shaped to produce a base, the depth of the base may be increased at will.

An important feature of the invention is the utilization of joint formers, producing 60 the spigot and faucet ends as the means for retaining the outer casing of the mold in its proper form during the manufacture of the pipe.

For packing the material into the mold I 65 obtain the best results by subjecting it as it is placed therein to the action of a machine made and operating according to my previous British Patent No. 5881 of 1906.

In an advantageous form of the mold the 70 outer casing is made to spring outward slightly to clear the pipe when the bolts detachably securing the same to the end plates are released. The attaching bolts are preferably hinged to the side of the outer casing 75 and arranged to swing into notches formed in the end plates.

To make the invention the better understood reference is had to the accompanying drawings, wherein,

Figure 1, is an end sectional elevation of a circular pipe mold constructed under the present invention, the section being taken on the line I—I of Fig. 2 and looking in the direction of the arrows. Fig. 2 is a side 85 sectional elevation of the mold on the line II—II of Fig. 1. Figs. 3 and 4 are respectively plan and side views of the wedge shaped slide or key employed for expanding and circumferentially completing the inner 90 casing of the mold. Figs. 5 and 6 are detail views to a larger scale illustrative of the pipe joint formers. Fig. 7, is a similar and sectional view to Fig. 1 illustrating the application of the invention to the manufacture 95 of egg-shaped pipes. Figs. 8 and 9 are plan and side views of the bolts for securing the outer casing and end plates of the mold together. Fig. 10 is a bottom view of Fig. 1.

a designates the inner casing or core of 100 the mold, which may be of steel plate bent to a cylindrical form, as shown in Fig. 1, or to an egg-shaped form, as shown in Fig. 7, according to the shape of the pipe to be made. This inner casing or core is arranged 105 circumferentially discontinuous along a line parallel to the longitudinal axis of the mold, in order that it may be circumferentially expanded throughout its length, as by means of a suitable wedging action. The 110

location of this line of separation of the inner casing or core during the manufacture of the pipe will generally be arranged correspondingly to that side of the pipe which will be uppermost in use. The arrangement of the inner casing or core is such that when, after having been distended, the distending means is removed, the inner casing will contract somewhat to facilitate its withdrawal from the pipe made around it. For convenience in withdrawing the pipe, a pair of hand-holds b, b^1 are attached to the inside of the casing a at each end thereof.

A convenient form of distending means is illustrated by C Figs. 3 and 4 and in cross-section in Figs. 1 and 7, and consists of a slightly tapering slide or wedge of inverted T shape in cross section. The base of the slide or wedge e is made to a curvature corresponding to the desired complete curvature of the casing when distended by the wedge, and is rabbeted along the longitudinal edges to fit over the edges d, d^1 of the interrupted casing a , and under and between longitudinal guides e, e^1 attached to the casing a adjacent to the edges d, d^1 . In order to avoid damaging the slide by hammering it into position its ends may be protected by shields such as is indicated by c^1 Figs. 3 and 4.

To fit over the ends of the casing a as shown in Fig. 2, end plates f, f^1 are provided. These end plates have flanges g, g^1 shaped to serve as male and female joint formers respectively, that designated g , forming the female joint, and g^1 the male joint. The facing sides of the end plates are recessed to form abutting shoulders h, h^1 for the ends of the outer casing, and notches i are formed around the end plates for receiving bolts secured to the outer casing for fastening this and the end plates together. The outline of the end plates f, f^1 is arranged to follow the shape in cross section of the inner casing a , except at that portion of the completed mold which will correspond with the foot of the pipe, at which portion the outline of the end plates is correspondingly changed as shown in Figs. 1 and 7. The abutting shoulders h, h^1 follow the outline of the end plates to insure a corresponding outline of the outer casing when this is positioned.

The outer casing j is formed by a channel shaped bent plate advantageously of steel, which may be stiffened along its horizontal and vertical edges as by angle irons j^1 . Normally the outer casing j , corresponds only approximately to the outline of the abutting shoulders h, h^1 , i. e. it is arranged to spring outwardly somewhat when it is disconnected from the end plates in order that it shall clear the pipe made within it. To secure the casing j and the end plates together, a convenient arrangement consists in hinging a number of screw bolts k , corresponding to

the number of notches i in the end plates, to the outer casing, at each end. As shown the bolts k are hinged to brackets l riveted to the casing and are each provided with an eye nut m . With this arrangement the bolts can be readily swung into the notches i and secured by the nuts m , thereby securely fastening the outer casing and the end plates together. To facilitate removal of the outer casing j from the pipe when made, lifting handles n are provided at each side as shown in Fig. 1.

When a depth of the pipe base is desired greater than that normally allowed for by the mold side and end boards forming respectively a continuation of the outer casing j and the end plates f, f^1 , can be utilized to that end. To contract the outer casing when bolting this to the end plates, a clamp may be used, while for long pipes, transverse connecting bars will advantageously be secured at intervals to the longitudinal edges of the outer casing, in order to avoid springing outwardly intermediate of the end plates, especially during the packing of the conglomerate in the pipe chamber.

With a mold according to this invention I find I am able to manufacture pipes of an artificial conglomerate with greater facility and with better results than has obtained with molds heretofore employed.

Having now particularly described and ascertained the nature of my said invention and in what manner the same is to be performed I declare that what I claim is:—

1. A pipe mold comprising a contractile core, an outer expandable horse-shoe shaped casing of sheet metal having longitudinal edges which form the inlet opening arranged in a horizontal plane and which when released springs outwardly and in opening acts through its sides acting as lifting supporting members to automatically bodily separate and free itself from the pipe and take the weight of the casing off the back of the pipe, end plates to which said core and said expandable casing are removably secured, bearing surfaces on the facing sides of said plates, said bearing surfaces following the contour of the exterior of the pipe and being adapted to permit the expandable casing to so separate and free itself from the pipe when said casing is released, said end plates being each provided with a central opening within which the said core is adapted to be expanded, and means for holding said expandable casing in fixed relation to said core and in fluid tight relation to said end plates.

2. A pipe mold constituting a self-contained unit comprising a core; an outer expandable casing of sheet metal acting as one integral unit, and having longitudinal edges which form the inlet opening arranged in a horizontal plane and which when released

springs outwardly to clear the pipe from the mold; end plates each provided with a central opening within which the contractile core is adapted to be expanded; bearing surfaces, following the contour of the exterior of the pipe, provided on the facing sides of said end plates; and fastening means comprising a series of screwed shanks pivotally connected to the casing and adapted to engage a corresponding series of slots provided around the outer portions of the end plates

5
10

and to be held therein by bolts (*m*) whereby also the edges of the casing are drawn against the end plates with a pressure producing substantially a liquid tight joint and the parts of the mold are rigidly assembled.

15

In testimony whereof I affix my signature in presence of two witnesses.

PETER BURD JAGGER.
